[57] CLAIM

The ornamental design for a control valve housing, as shown and described.

DESCRIPTION

FIG. 1 is a side elevational view of a control valve housing showing my new design, with all other sides being identical to that shown. The broken line showing is for illustrative purposes only and forms no part of the claimed design;

FIG. 2 is a top plan view of my design; and,

FIG. 3 is a bottom plan view of my design.

*FIG. 1**FIG. 2**FIG. 3*
